CLAIM

The ornamental design for a wall plate, as shown and described.

DESCRIPTION

FIG. 1 is a perspective photographic view of a wall plate for a switch illustrating my new design.

FIG. 2 is a photographic front elevational view of the wall plate of FIG. 1.

FIG. 3 is a photographic front elevational view of a wall plate for a duplex receptacle illustrating my new design.

FIG. 4 is a photographic front elevational view of a wall plate for two side-by-side switches illustrating my new design.

FIG. 5 is a photographic front elevational view of a wall plate for a side-by-side receptacle and switch illustrating my new design.

FIG. 6 is a rear elevational view of the wall plate of FIG. 1.

FIG. 7 is a side elevational view of the wall plate as in FIG. 1.

FIG. 8 is an end plan of the wall plate of FIG. 1.

FIG. 9 is a vertical sectional view of the wall plate of FIG. 1 taken in the direction of arrows on line 9—9 of FIG. 6;

FIG. 10 is a horizontal sectional view of the wall plate of FIG. 1 taken in the direction of the arrows on line 10—10 of FIG. 6.
